UNITED STATES PATENT OFFICE

CHARLES F. KUHNLA, OF JAMAICA, NEW YORK, ASSIGNOR TO AUGUST KUHNLA, INC.,
A CORPORATION OF NEW YORK

BUILDING STRUCTURE

Application filed September 11, 1928. Serial No. 305,237.

This invention relates particularly to superstructures of buildings, such as skylight structures, and more particularly to the construction of the longitudinal ridge piece forming the comb of such superstructure. Heretofore commonly this ridge piece has been a wooden beam forming a ridge pole. These wooden ridge poles, particularly for skylight structures, have proved generally unsatisfactory. An expensive grade of lumber must be used, they are not sufficiently rigid, they shut out considerable light, they must be securely protected from the weather, present difficulties in securing the attachment of rafters and of the necessary pulley blocks, etc.

An object of this invention is to provide a roofing beam and more particularly a ridge piece of improved construction which is particularly adapted for use in skylight structures and which will meet the particular requirements of such structures in a satisfactory manner. Other more particular objects and advantages of the invention will hereinafter appear.

A roofing beam or ridge piece according to the present invention is formed entirely of metal and comprises various features of construction and combinations of parts, as will appear from the following description.

One embodiment of the invention is illustrated in the accompanying drawings and this embodiment will now be particularly described, after which the invention will be pointed out in claims, reference now being had to the drawings, in which:

Fig. 1 is a transverse vertical section of a portion of a skylight roof structure in which the invention is embodied; and

Fig. 2 is a reduced non-central vertical longitudinal section of the same.

The particular manner of practically carrying out the invention shown in the accompanying drawings will now be described. A horizontal ridge piece is shown as having a central steel core bar 1, which is flat and disposed vertically on edge so as to provide adequate strength with minimum lateral extension. Excepting at its lower edge, this core bar is covered and completely enclosed by a one piece sheet metal jacket. This jacket

comprises a narrow curved top 2 connecting together upper parallel wall portions 3 which telescope over and lie flat against the upper portion of the core bar 1. Intermediate of the width of the core bar 1 the jacket on its opposite sides is bulged outwardly to form hollow inclined roof-supporting ledges, each of which comprises an upper flat outwardly inclined ledge portion 4 and a downwardly extending inwardly inclined bracing or leg portion 5 which is shown as extending into contact with the adjacent side of the core bar 1.

Immediately at the downward termination of the brace legs 5 there are formed outwardly projecting downwardly inclined drip ledges in compact folded form each comprising an upper wall 6 and a lower wall 7 which lies flat against the upper wall 6, thereby providing a maximum of free or open space below these drip ledges which may be utilized for a purpose which will presently appear. From the inner termination of the lower walls 7 of these drip ledges parallel vertical walls 8 respectively lie flat against the lower marginal portion of the core bar 1 and extend downward to its lower edge. Lower horizontally aligned flanges 9 project outwardly from the lower termination of the respective walls 8 at right angles thereto and substantially flush with the lower edge of the core bar 1.

The lower edge of the core bar 1 is covered by a sheet metal cover strip or finish strip 10 which lies flat against and completely covers the lower sides of the right angular flanges 9. The marginal edges of this cover strip 10 are turned inward to form flanges 11 which lie flat against the upper surface of the right angular jacket flanges 9. These flanges 11 of the strip 10 are shown as extending inwardly to the respective vertical walls 8 so as to cover completely the jacket flanges 9.

It will be noted that in this ridge piece construction the outwardly bulged roof-supporting ledges comprise the ledge forming portions 4 and the brace legs 5; the folded drip ledges having the upper and lower walls 6 and 7; the right angular lower flanges 9; and the cover strip 10 with its inturned 100

flanges 11; all contribute substantially to the lateral strength and rigidity or stiffness of the ridge piece as a whole and reinforce the enclosed core bar 1, to prevent its springing or bending of the ridge piece in a horizontal or lateral direction. At the same time these laterally projecting sheet metal parts perform other functions as will presently more clearly appear.

10 A superstructure of the kind in which this invention is embodied is provided with ventilating sashes, doors, or other closures which may be opened or closed as desired. The devices commonly employed for operating these closures include cables running over various pulleys. Among the more important of these pulleys are some which are carried by the ridge piece of the superstructure, and in carrying out the present invention provision is therefore made for such pulleys.

15 While the two three-ply flanges produced by the jacket flanges 9 and the cover strip 10 together with its inturned flanges 11, have considerable strength and rigidity, such flanges might not be sufficiently rigid and strong to support the usual pulley blocks, and hence it is desirable to provide a reinforcement of these flanges for that purpose. Accordingly, in carrying out the invention, at 20 each place along the ridge piece where a pulley block is attached thereto, a pair of oppositely arranged angle bars 12 are fitted into the corners up against the vertical walls 8 of the core jackets and overlie the inturned flanges 11 of the lower strip 10. These angle bars 12 are of suitable length and are firmly secured to the core bar 1, through the jacket walls 8, by means of bolts 13.

25 The pulley block shown has an upper plate 14 which fits flat up against the bottom surface of the lower cover strip 10 and which at its lateral margins is firmly secured, through the right angular flanges of the jacket, to the angle bars 12 by means of bolts 15, adjacent 30 to the ends of this plate, which is shown as coterminous with the angle bars 12.

35 The drawings show only the middle portion of the improved ridge piece which of course is of whatever length that may be required in any particular roof structure. Any 40 number of pulley blocks may be arranged along the length of this ridge piece, commonly there being one at the middle and others adjacent the respective ends. These pulley blocks each may carry substantially any desired 45 number of pulleys arranged in any suitable way that may be required for the particular installation. For example, instead of the pulley block shown in the drawings which 50 carries two pulleys and has an elongated upper plate 14, in some cases there is employed a pulley block having a circular upper plate with the pulleys arranged radially around its 55 peripheral margin.

60 65 Rafters in any desired number are secured

at their upper or inner ends to the ridge piece at the opposite sides thereof and the end portions of two oppositely arranged rafters are shown in the drawings. The rafters shown are of a construction somewhat similar to that of the above described ridge piece. 70 Such a rafter is shown as having a core bar 16, the upper end of which may be firmly secured to the core bar 1 of the ridge piece in any suitable manner. This core bar 16 is covered and enclosed by a one-piece sheet metal jacket closed at the top and having side walls 17 fitting snugly telescopically over the core bar 16.

75 At the lower termination of the walls 17, there are provided hollow roof-supporting ledges comprising right-angular walls 18 and inwardly inclined converging brace portions 19, from which extend outwardly projecting aligned flanges 20 the edge portions 21 of which are turned upwardly to form a trough or gutter. It will be noted that the brace walls 19 meet below the core bar 16 and may there be soldered together for additional strength. The end of the rafter jacket may 80 be secured to the side of the ridge piece jacket in any suitable manner, which may include soldering. In some cases of relatively small and light structures the rafter core bar 16 may be omitted, sufficient strength and rigidity being provided by the sheet metal jacket 85 construction above described.

90 The rafter construction further includes a one-piece sheet metal cap strip having a rounded closed top and spaced parallel side walls 22 which fit snugly over the similar walls 17 of the core jacket and further comprises outwardly projecting slightly inclined flanges 23 which terminates in further inclined edge portions 24 which extend over 95 the marginal side edges of the roofing.

100 The ridge piece having the core bar 1 includes in its construction a one-piece sheet metal cap or top strip which is substantially of inverted trough-shape, being closed at the 105 top by a short rounded or curved portion 25 from which relatively narrow spaced parallel walls 26 extend downward and fit snugly over the walls 3 of the core jacket. From these walls 26 there project oppositely extending 110 inclined wings 27, the outer margins of which are turned downwardly at substantially right angles to form flanges 28 which extend down to the roofing, so that this cap or ridge piece top strip forms a water shed for the upper 115 marginal edge of the roofing.

120 The invention is shown in the drawings as carried out in a skylight structure and accordingly the roofing comprises glass plates 29 which are held in place at their upper or inner margins by the downturned flanges 28 of the ridge piece and at their lateral margins by the flange margins 24 of the rafter cap. The roofing structure above described 125 as embodying the present invention is suitable 130

to be employed either in a simple double pitch gabled roof or in a hipped roof, or in other forms of roof, according to the particular requirements.

5 It is obvious that various modifications may be made in the construction shown in the drawings and above particularly described, within the principle and scope of the invention as defined in the appended claims.

10 I claim:

1. In a building structure, a ridge piece comprising a straight flat metal core bar arranged vertically edgewise, a one-piece sheet metal jacket snugly telescoped over the upper edge of the core bar and completely covering both its sides, said jacket in its upper and lower portions lying flat against the upper and lower portions of both sides of the core bar and at opposite points intermediate of the width of the core bar such jacket being bulged outwardly at both sides to form a hollow downwardly inclined roof-supporting ledge, an outwardly inclined folded drip ledge being formed on each of the sides of the jacket immediately below its said hollow roof-supporting ledge, the lower edge portions of the two sides of the jacket being turned outwardly at right angles to form flanges in alignment with each other substantially flush with the lower edge of the core bar, a sheet metal lower cover strip lying flat against the lower sides of the said lower right angular flanges completely covering said flanges and the lower edge of the core bar and at its edges flanged inwardly over and substantially completely covering the upper sides of said right angular jacket flanges, and angle bars at opposite sides of the core bar overlying the inturned flanges of the lower cover strip and bolted to the core bar through its jacket to provide a support for a pulley block.

2. The invention defined in claim 1, in combination with a pulley block having an upper plate fitting up against the bottom surface of said cover strip and bolted to the said angle bars through said right angular flanges of the jacket and through the said cover strip and its inturned flanges.

3. In a building structure, a ridge piece comprising a straight flat metal core bar arranged vertically edgewise, a one-piece sheet metal jacket snugly telescoped over the upper edge of the core bar and completely covering both of its sides, said jacket in its upper and lower portions lying flat against the upper and lower portions of both sides of the core bar and at opposite points intermediate of the width of the core bar such jacket being bulged outwardly at both sides to form a hollow roof-supporting ledge, the lower edge portions of the two sides of the jacket being turned outwardly at right angles to form flanges in alignment with each other substantially flush with the lower edge of the

core bar, and a folded outwardly and downwardly inclined drip ledge formed on each of the sides of said jacket below the said hollow roof-supporting ledges.

4. In a building structure, a ridge piece comprising a straight flat metal core bar arranged vertically edgewise, a one-piece sheet metal jacket snugly telescoped over the upper edge of the core bar and completely covering both of its sides, said jacket having flat aligned upper and lower portions lying flat against the upper and lower portions of both sides of the core bar and at opposite points between the said flat upper and lower portions and intermediate of the width of the core bar such jacket being bulged outwardly at both sides to form a hollow downwardly inclined roof-supporting ledge, an outwardly and downwardly inclined folded drip ledge formed on each of the sides of the said jacket immediately below its said hollow roof-supporting ledge and at the top of its said flat lower portion, the said lower flat portions of the two sides of the jacket extending from the said drip ledge down to the lower edge of the core bar in contact therewith and being turned outwardly at right angles to form flat flanges in alignment with each other substantially flush with the lower edge of the core bar, and a flat sheet metal lower cover strip lying flat against the lower sides of the said lower flat right angular flanges completely covering said flanges and the lower edge of the core bar and at its edges flanged inwardly over and substantially completely covering the flat upper sides of said right angular jacket flanges.

5. The invention defined in claim 4, in combination with a one-piece inverted trough-shaped sheet metal cap strip having spaced parallel side walls fitting snugly telescoped part way over the said upper portion of the enclosing jacket at the upper edge of the core bar and having oppositely extending downwardly inclined wings spaced above the roofing and the outer margins of which are turned downwardly and inwardly at an angle to form flanges extending down to the roofing so that such cap strip forms a water shed for the upper marginal edges of the roofing which overlie said roof-supporting ledges.

In witness whereof, I hereunto subscribe my signature.

CHARLES F. KUHNLA.
